Haworth & Hawson

UNITED STATES PATENT OFFICE.

FRANK CRAWFORD, SR., OF NEW BRUNSWICK, NEW JERSEY.

THREAD GUIDE FOR STOP MOTIONS.

Application filed August 31, 1923. Serial No. 660,331.

To all whom it may concern:

Be it known that I, FRANK CRAWFORD, Sr., a citizen of the United States, residing in New Brunswick, Middlesex County, 5 New Jersey, have invented certain Improvements in Thread Guides for Stop Motions, of which the following is a specification.

My invention relates to certain improvements in thread guides for stop motions, 10 especially the stop motions of knitting machines.

The object of my invention is to design the thread guide so that it will hold the 15 thread in the proper position and will act when a thread is caught, to release the thread and to actuate the mechanism for stopping the machine.

In the accompanying drawings:

20 Fig. 1 is a perspective view of sufficient of the frame of a stop motion to illustrate my invention;

Fig. 2 is a plan view;

25 Fig. 3 is a side view, showing the casing in section; and

Fig. 4 is an end view of the thread guide.

Referring to the drawings, 1 is the casing, 30 which encloses part of the mechanism of the stop motion that controls the power mechanism of a knitting machine, in the present instance. 2 is a bracket that projects from the casing. Under the bracket is a shaft 3, which extends into the casing 1 and is mounted in a bearing 14 under the bracket 35 2. The shaft 3 has an arm 4 at its outer end. This arm is shaped, as shown clearly in Figs. 1 and 4, and is curved and rounded in cross section for the passage of the thread.

40 Mounted on the bracket 2 is a plate 7, which is held in place by a screw 8 and a tongue 9, which is bent from the plate and extends into an opening 10, Fig. 2. This plate is bent downwards to form a guide

45 11 having a beak-shaped end 12. This

beak-shaped end extends into the slot 6 when the arm 4 is in the raised position.

At the rear of the guide 11 is a segmental projection 13, which extends through the slot 5 and remains in the slot, irrespective 50 of the position of the arm.

The arm and the guide form a passage for the thread. The segmental projection 13 prevents the thread passing up to the shaft and limits its downward movement 55 while the beak-shaped end of the guide limits the movement in the other direction.

When a thread is caught, it pulls the arm 4 down to the position shown by dotted lines in Fig. 4. This movement releases 60 the thread and actuates the stop mechanism, which stops the knitting machine.

I claim:

1. The combination in a thread guide for stop motions, of a casing having a bracket; 65 a shaft under the bracket, the outer end of the shaft being supported by the bracket; a curved arm mounted on the shaft and rounded in cross section, said arm having a slot near its outer end; a plate secured to the bracket and bent downwards to form 70 a guide; a beak-shaped end on the guide extending into the slot in the arm; and a projection acting as a guard to prevent the thread passing towards the shaft. 75

2. The combination in a thread guide for stop motions, of a casing having a bracket; a shaft under the bracket, the outer end of the shaft being supported by the bracket; a curved arm mounted on the shaft 80 and rounded in cross section, said arm having slots one near the outer end and one some distance from the end; a plate secured to the bracket and bent downwards to form a guide; a beak-shaped end on the guide extending into the slot at the end of the arm; and a projection on the guide extending through another slot. 85

FRANK CRAWFORD, SR.
